Primary Examiner — Anhdao Doan(74) *Attorney, Agent, or Firm* — Scully Scott Murphy and Presser(57) **CLAIM**

The ornamental design for a fluid application apparatus, as shown and described.

DESCRIPTION

FIG. 1 is a perspective view of a fluid application apparatus showing my new design;

FIG. 2 is an alternative perspective view thereof;

FIG. 3 is a front elevation view thereof;

FIG. 4 is a rear elevation view thereof;

FIG. 5 is a side elevation view thereof;

FIG. 6 is an opposite side elevation view thereof; and,

FIG. 7 is a top plan view thereof.

The broken lines showing the unshaded region of the fluid application apparatus are for environmental purposes only and form no part of the claimed design.
